INDUCTION TYPE TIME-DELAY RELAY

Herbert J. Carlin, East Orange, N. J., and Bert V. Heard, Portland, Oreg., assignors to Westinghouse Electric Corporation, a corporation of Pennsylvania

Application October 12, 1944, Serial No. 558,316

12 Claims. (Cl. 175—294)

1

This invention relates to electroresponsive instruments and it has particular relation to an induction type relay having a time delay in operation, which varies as an inverse function of the electrical quantity to which the relay responds.

The induction principle of operation is employed in many electrical instruments such as integrating and indicating measuring instruments and relays. Such instruments may be designed for response to various electrical quantities such as voltage, current and power. Since the invention is particularly suitable for time-delay electrical relays, the discussion will be directed to induction-type overcurrent relays which are designed for operation with time delay.

An induction-type relay includes an electroconductive armature which is mounted for rotation. In order to retard rotation of the armature, damping means is provided which may take the form of one or more permanent magnets which produce magnetic flux through the armature. The retarding force developed by such permanent magnets varies in accordance with the angular velocity of rotation of the armature.

In order to obtain a force acting on the armature of an induction relay to produce rotation thereof, a pair of alternating magnetic fluxes ϕ_1 and ϕ_2 are applied to the armature. These magnetic fluxes are displaced both in space and in time phase from each other to provide a shifting magnetic field which urges the armature in a predetermined direction. The angle of phase displacement between the magnetic fluxes may be represented by the reference character θ . In conventional designs, the angle θ may have an optimum value of the order of 45°. If k designates a suitable constant, the torque T applied to the armature of the induction type relay may be represented by the following expression:

$$T = k\phi_1\phi_2 \sin \theta$$

Induction type relays are provided with magnetic structures or cores which provide paths of low reluctance for the magnetic fluxes ϕ_1 and ϕ_2 . If the relay is to develop a desirably large torque at large values of current, the magnetic core thereof should not saturate when energized by such currents. On the other hand, it is difficult to provide adequate torque in the low current operating range of the relay unless the magnetic core of the relay is designed to saturate when energized by large currents. For these reasons, it is the practice to employ a magnetic core which saturates when energized by large currents which are within the operating range of the relay. In a conventional induction-type overcurrent relay,

2

the ratio of maximum to minimum current in the operating range of the relay may be of the order of 20 to 1.

For many applications, it is desirable that a relay operate with inverse time delay. This means that the time of operation of the relay varies as an inverse function of the magnitude of the electrical quantity to which the relay responds over the entire operating range of the relay.

10 Saturation of the magnetic core has an adverse effect on the inverse time delay characteristics of the relay. Such saturation restricts the increase of either or both of the magnetic fluxes ϕ_1 and ϕ_2 . Consequently, after saturation of the 15 magnetic core, the time of operation of the relay does not decrease at the desired rapid rate with an increase in energizing current.

In accordance with the invention, the effects of saturation of the magnetic core of a relay are 20 compensated by suitable changes in the angle of phase displacement θ between the two magnetic fluxes ϕ_1 and ϕ_2 . By reference to the above-noted formula for torque, it will be observed that the effect of saturation of the magnetic core of an 25 induction relay is to restrict the increase of magnetic fluxes ϕ_1 and ϕ_2 . In accordance with the invention, this restriction is offset or compensated by suitably increasing the value of the expression:

$$\sin \theta$$

30 In this way, an induction type relay can be designed to have desirable inverse time delay characteristics over the entire operating range thereof.

It is, therefore, an object of the present invention to provide an electroresponsive instrument having improved torque characteristics.

It is a further object of the invention to provide a time-delay relay wherein effects of magnetic saturation are substantially compensated.

40 It is a still further object of the invention to provide an induction type relay having an armature responsive to the torque developed by two phase-displaced, alternating magnetic fluxes 45 wherein the phase displacement between the magnetic fluxes is varied in accordance with the energization of the relay to compensate for the effects of saturation of the magnetic core of the relay on the torque developed thereby.

50 Other objects of the invention will be apparent from the following description taken in conjunction with the accompanying drawing, in which:

Figure 1 is a graphical representation of operating curves for a time delay relay;

Fig. 2 is a schematic representation, with parts

shown in plan elevation, of a relay system embodying the invention;

Fig. 3 is a plan view, with parts broken away, of an induction disk relay embodying certain features of the invention;

Fig. 4 is a vertical sectional view taken along the line IV—IV of Fig. 3;

Fig. 5 is a schematic development view showing the construction of the relay of Figs. 3 and 4 spread out in a plane and showing suitable connections for the relay; and

Figs. 6 and 7 are vector representations showing relations of currents in the relay of Figs. 3, 4 and 5.

Referring to the drawing, Fig. 1 shows the operating characteristics of conventional induction type inverse time-delay relays. In Fig. 1, ordinates represent time delays in operation of the relays and abscissae represent values of energizing current. The curve 1 represents a relay which is designed for inverse time-delay operation whereas the curve 3 represents a relay which is designed for what is known as very-inverse time-delay operation. It will be noted that for lower current values, the relays represented by the curves 1 and 3 have time delays of operation which decrease rapidly with an increase in energizing current. However, for larger current values, the curves appear to approach asymptotes which are horizontal in Fig. 1. Consequently, in this latter range in increase in energizing current is not accompanied by a substantial decrease in the operating time of the relays. As previously explained, it is desirable that the inverse characteristics of the relays be available over the entire operating ranges thereof.

The relay system illustrated in Fig. 2 is capable of providing improved inverse characteristics. In Fig. 2, a relay is represented which includes an electroconductive armature 5 in the form of a disk. This armature is mounted for rotation on a shaft 7 which carries a movable contact member 9. Rotation of the shaft 7 carries the movable contact 9 into and out of engagement with stationary contacts 11. Closure of the contacts 11 may be employed to complete an electrical circuit for any desired control or protective function. A spiral spring 13 is provided for biasing the shaft 7 in a predetermined direction. For the purpose of discussion, it will be assumed that the spring 13 biases the shaft to urge the movable contact member 9 away from the stationary contacts 11.

Rotation of the armature 5 is retarded by suitable damping means which is illustrated in Fig. 2 as a permanent magnet 15. The armature 5 is positioned for rotation between the pole faces of the permanent magnet. As well understood in the art, the damping force provided by the permanent magnet 15 varies in accordance with the rate of rotation of the armature 5.

For applying an operating torque to the armature 5, windings 17, 19, and 21 are provided which, when energized by alternating current, direct alternating magnetic fluxes in a path cutting the armature 5. The magnetic fluxes of windings 17—19, and 21 correspond, respectively, to the previously-mentioned fluxes ϕ_1 and ϕ_2 . The magnetic flux of windings 17 and 19 and the magnetic flux of the winding 21 are displaced in space with respect to the armature 5. If the magnetic flux of windings 17 and 19 also is displaced in time phase from the flux of the winding 21, the magnetic fluxes develop a shifting magnetic field

which produces a torque acting on the armature 5.

In order to provide magnetic paths of low reluctance for the magnetic flux produced by the various windings, a magnetic structure or core 23 is provided which includes a pair of pole pieces 25 and 27 for the windings 17 and 19 and a pole piece 29 for the winding 21. These pole pieces are spaced to define an air gap 31 within which the armature 5 is positioned for rotation. The construction and operation of the specific portions of Fig. 2 which thus far have been specifically referred to are well understood in the art and are disclosed, in part, in the Relay Handbook published in 1926 by the National Electric Light Association of New York city. Specific reference may be made to pages 104 to 125 of this Handbook wherein induction overcurrent relays operating with the time delay are discussed.

Continuing the discussion of Fig. 2, the windings 17, 19, and 21 may be connected for energization in any suitable manner. Let it be assumed that the relay of Fig. 2 is to be energized in accordance with the current flowing in an alternating-current circuit represented by conductors L1 and L2. Such energization may be derived from the circuit through a current transformer 33. The windings 17, 19 and 21 and a resistor 35 are connected in series across the secondary of the current transformer 33. The resistor 35 will be discussed further below. It will be understood that the windings 17 and 19 are so connected that when the winding 17 directs magnetic flux downwardly in the pole piece 25, the winding 19 directs magnetic flux upwardly in the pole piece 27. The direction in which the magnetic field produced by the windings urges the armature 5, may be reversed by reversing the connection of the terminals of the winding 21.

Since the windings 17, 19 and 21 are connected in series, the current flowing therethrough and the magnetic fluxes produced by said current are in phase. To lag the air-gap magnetic flux ϕ_1 as produced by the winding 21 with respect to the air gap flux ϕ_2 as produced by the windings 17 and 19, a closed circuit lagging winding 37 is disposed about the pole piece 29. When the circuit of the lagging winding 37 is closed, a torque is applied to the armature 5 which urges the movable contact member 9 towards the stationary contacts 11.

In considering the phase displacement between the magnetic fluxes ϕ_1 and ϕ_2 it may be noted that in an induction relay of conventional type the angle of phase displacement between the magnetic fluxes applied to the relay armature may have a value of the order of 45°. However, to obtain a maximum of inverseness, the design of the relay shown in Fig. 2 may be such that with low multiples of minimum trip current in the relay, the phase displacement of the fluxes ϕ_1 and ϕ_2 is considerably less than 45°.

It will be recalled that saturation of the magnetic structure 23 in response to energization of the relay by large currents tends to restrict the increase of one or both magnetic fluxes ϕ_1 and ϕ_2 and adversely affects the inverse characteristics of the time delay provided by the relay. To compensate for the effects of such saturation, an impedance is included in the closed circuit of the lagging winding 37 which varies, in magnitude as a function of the energization of the relay. Such an impedance is represented in Fig. 2 by a winding 39 having a closed magnetic core 41. By saturating the magnetic core 41, the re-

active impedance introduced in the closed circuit of the lagging winding 37 by the winding 39 may be reduced. Since the lagging of the magnetic flux ϕ_1 by the lagging winding 37 increases as the impedance of the closed circuit of the lagging winding 37 decreases, it follows that saturation of the magnetic core 41 is accompanied by an increase in the angle of phase displacement θ between the two magnetic fluxes ϕ_1 and ϕ_2 . By suitable proportioning, the increase in the angle of phase displacement θ may compensate substantially for the restriction in increase in either or both of the magnetic fluxes ϕ_1 and ϕ_2 resulting from saturation of the magnetic structure 23.

Saturation of the magnetic core 41 is controlled by a winding 43 which is connected to the output terminals of a rectifier 45. The rectifier 45 may be of any suitable construction. Preferably it is a full-wave rectifier. For example, it may be formed of a barrier-layer units, such as copper-oxide rectifiers which are arranged in the form of a rectifying bridge. If desired, the rectifier may include a filter for eliminating alternating-current ripple, from the output thereof, but ordinarily such a filter is not required. The input terminals of the rectifier 45 are connected across the resistor 35. Consequently, the voltage applied across the input terminals of the rectifier is equal to the voltage drop across the resistor 35. This voltage drop varies in accordance with the relay energizing current derived from the conductors L1 and L2.

The proportions are such that the magnetic core 41 and the magnetic structure 23 start to saturate approximately at the same time. Since the characteristic of the relay is satisfactory for low-current values, the magnetic core 41 may be constructed of a material which does not saturate or change in permeability appreciably at low-current values. For example, the magnetic core 41 may be formed of a magnetic alloy similar to that disclosed in the Yensen Patent 1,807,021.

To facilitate an understanding of the invention, a brief discussion of the operation of the system illustrated in Fig. 2 will be given. The windings 17, 19, and 21 are connected for energization in accordance with the current flowing through the circuit represented by the conductors L1 and L2. As the current flowing through the circuit increases from zero, the air gap magnetic fluxes ϕ_1 and ϕ_2 produced by the windings increase. Consequently, the torque applied to the armature 5 thereby increases in accordance with the square of the current. At a predetermined value of current, the torque overcomes the bias of the spring 13 and moves the movable contact member 9 towards the stationary contacts 11. Such movement is retarded by the permanent magnet 15 which develops a retarding force varying in accordance with the rate of rotation of the armature 5. As the current flowing through the associated circuit continues to increase, the armature 5 moves with increasing velocity until the magnetic structure 23 begins to saturate.

The term "saturation" refers to decremental permeability or effective decrease in permeability of the magnetic structure. In the region of saturation, the magnetic structure undergoes a rapid reduction in permeability. As a result of saturation, either or both of the magnetic fluxes ϕ_1 and ϕ_2 fails to increase in accordance with the current flowing through the associated circuit. However, as the magnetic structure 23 saturates, the magnetic core 41 also saturates. Because of

the saturation of the magnetic core 41, the impedance of the closed circuit including the lagging winding 37 decreases and the angle of phase displacement between the magnetic fluxes ϕ_1 and ϕ_2 increases. By proper proportioning of the parts, the increase in the angle may compensate substantially for the effect of the saturation of the magnetic structure 23 on the torque of the relay, and the torque applied to the armature 5 by the air gap fluxes ϕ_1 and ϕ_2 continues to increase substantially in accordance with the square of the current flowing through the circuit represented by the conductors L1 and L2. The proportions may be such that when the relay is energized by the maximum current in the range to which it is to respond, the angle of phase displacement θ may have an optimum value of the order of 45°. For lower values of current, when the magnetic structure 23 and the magnetic core 41 are saturated to a lesser degree or are unsaturated, the angle of phase displacement has smaller values. The increase in saturation of the magnetic structure 23 and the magnetic core 41 may be continuous over a substantial range of variation of applied current.

The invention also may be embodied in a somewhat different relay structure. Referring to Figs. 3, 4 and 5, a relay is disclosed which includes the armature 5, shaft 7, movable contact member 9, stationary contacts 11, and spring 13. The shaft 7 is mounted for rotation in suitable bearings 7a. The stator associated with the armature 5 in Figs. 3, 4 and 5 includes a resultant magnetic structure which is formed by an upper magnetic structure 47 and a lower magnetic structure 49. The upper magnetic structure 47 comprises a plurality of pole pieces 51, 53, 55 and 57 which are angularly spaced by equal distances around the shaft 7. The magnetic pole pieces 51, 53, 55 and 57 have their upper ends magnetically connected by a magnetic ring or yoke 59. Each of the upper pole pieces has a magnetic pole-face member 61 disposed adjacent the upper face of the armature 5.

In a somewhat similar manner, the lower magnetic structure 49 includes a plurality of magnetic pole pieces 63, 65, 67 and 69 which have their lower ends connected by a magnetic ring or yoke 71. The upper ends of the lower pole pieces have magnetic pole-face members 73 which are positioned adjacent the lower face of the armature 5. The magnetic structures 47 and 49 are positioned angularly about the shaft 7 to bring each of the upper pole-face members 61 substantially between two of the lower pole-face members 73.

Each of the upper pole pieces has a separate winding 75 associated therewith. Similarly, each of the lower pole pieces has a separate winding 77 associated therewith. These windings may be of similar construction. For the purpose of discussion, it is assumed that the windings 75 are current-type windings having a number of turns of conductor capable of carrying large currents whereas the windings 77 are assumed to be low current-type windings having a larger number of turns designed to carry small currents.

The windings 77 when energized by an alternating-current produce a magnetic flux cutting the armature 5 which may be designated by the symbol ϕ_1 . Also, the upper windings 75 when energized by alternating current produce a magnetic flux which cuts the armature 5 and which may be designated by the symbol ϕ_2 . These magnetic fluxes are displaced in space from each

other. If the magnetic fluxes are displaced in time phase from each other by the angle θ and if K is a suitable constant, then the torque T applied by the magnetic fluxes to the armature 5 is represented by the well-known formula:

$$T = K\phi_1\phi_2 \sin \theta$$

If the relay of Figs. 3, 4 and 5 is to be employed as an overcurrent relay, connections similar to those illustrated in Fig. 5 may be employed. The alternating-current electrical circuit from which the relay is to be energized is represented by the same conductors L1 and L2. An autotransformer 79 has its primary winding connected to the electrical circuit for energization in accordance with the current flowing therein. Such connection may include an adjustable tap 81 for adjusting the energization of the relay. The windings 75 are connected in series through conductors 83 and 85 to a pair of secondary terminals of the autotransformer which are capable of supplying substantial current at low voltage to these current-type windings. The windings are so arranged that when the windings on the pole pieces 51 and 55 direct magnetic flux downwardly therein, the windings associated with the pole pieces 53 and 57 direct magnetic flux upwardly therein.

In a somewhat similar manner, the windings 77 are connected through conductors 87 and 89 across secondary terminals of the autotransformer 79 which are capable of supplying relatively smaller currents at larger voltages to these low-current type windings. In order to provide a desired phase displacement between current flowing in the windings 75 and current flowing in the windings 77, suitable impedances represented by resistors 91 and 93 are connected in series with the windings 77. The currents I_1 and I_2 which flow respectively through the windings 77 and 75 may be represented as shown in the vector diagram of Fig. 6, wherein the current I_1 leads the current I_2 by the angle θ . It will be understood that the windings 77 are so arranged that when the windings associated with the pole pieces 63 and 67 direct magnetic flux downwardly therein in the windings associated with the pole pieces 65 and 69 direct magnetic flux upwardly in the associated pole pieces. The structure of the relay illustrated in Figs. 3, 4 and 5 which thus far has been specifically referred to is illustrated and described in greater detail in the copending application of Bert V. Hoard, Serial No. 456,901, filed September 1, 1942, now Patent No. 2,379,905, issued July 10, 1945, and assigned to the same assignee to whom the present application is assigned.

In the relay of Figs. 3, 4 and 5, saturation of one or both magnetic structures 47 and 49 affects the relationship between the magnetic fluxes ϕ_1 and ϕ_2 and the current which energizes the relay. In order to compensate for restrictions on increase in magnetic flux imposed by saturation, the relay is so designed that the magnetic structures 47 and 49 do not saturate equally. It is permissible with the structure illustrated in Figs. 3, 4 and 5 to so construct the magnetic structure 47 that it does not saturate even when energized by the maximum current for which the relay is designed. This is permissible for the reason that the magnetic structure 49 is designed to saturate and limit the maximum voltage appearing across the relay. Preferably, all of the pole-face members 61 and 73 have cross sections sufficient to prevent saturation thereof. This is desirable for the reason that each of the pole-face members

carries both magnetic fluxes. To obtain saturation of the magnetic structure 49, the pole pieces 63, 65, 67, and 69 or the yoke 71 or all of these parts may be provided with a cross section sufficiently restricted to assure saturation thereof when the windings 77 are energized by current above a predetermined value but within the working range of the relay.

Saturation of the magnetic structure 49 decreases the reactive impedance offered to current I_1 flowing through the windings 77. Consequently, this current as the magnetic structure 49 saturates, increases more rapidly than the current flowing through the windings 75 and becomes more leading with respect to the current I_2 flowing through the windings 75. This is shown in Fig. 7 wherein the currents I_1 and I_2 are displaced in phase by an angle θ which is substantially larger than the corresponding angle θ of Fig. 6. For the reasons above set forth, the increase in the angle θ may be proportioned to compensate for the restrictions in the increase of the flux ϕ_1 imposed by saturation of the magnetic structure 49. By suitable proportioning, the operating torque applied to the armature 5 in Fig. 5 may be designed to vary in accordance with the square of the energizing current over substantially the entire range of operation of the relay.

As previously pointed out, rotation of a shaft 30 may be retarded by associating a permanent magnet with an electroconductive armature mounted on the shaft. Although such damping may be provided for the relay of Figs. 3, 4 and 5, a somewhat different damping arrangement is illustrated in Fig. 5.

In Fig. 5, a pair of half-wave rectifiers 95 and 97, together with resistors 99 and 101, are connected in series between conductors 87 and 89. The rectifiers may be of any suitable construction. Conveniently, they may be of the barrier-layer type, such as copper-oxide rectifiers. The rectifiers are so connected that they permit the flow of current therethrough in the same direction with respect to an intermediate terminal 103. In the specific embodiment of Fig. 5, the rectifiers 95 and 97 permit the flow of current only towards the terminal 103. Since the rectifiers are oppositely directed with respect to the series circuit which includes the resistors 99 and 101, current 50 can not flow directly through such series circuit.

The terminal 103 is connected by a conductor 105 to one terminal on each of the windings 77 associated with the pole pieces 65 and 67. The connections are such that when the conductor 55 87 is positive with respect to the conductor 89, current flows from the conductor 87 through the resistor 101, the rectifier 97, the terminal 103, the conductor 105, the windings 77 associated with the pole pieces 65 and 63, and the resistor 60 91 to the conductor 89. On the other hand when the conductor 89 is positive with respect to the conductor 87, current flows from the conductor 89 through the resistor 99, the rectifier 95, the terminal 103, the conductor 105, the windings 77 65 associated with the pole pieces 67 and 69 and the resistor 93 to the conductor 87. Consequently, the windings 77 are energized by pulsating direct current and serve to produce a damping force acting on the armature 5. As previously explained, the damping force varies as the velocity of rotation of the armature 5.

In addition, the direct current flowing through the windings 77 contributes to the saturation of the magnetic structure 49. Consequently, the proportions of the magnetic structure 49 should

be such that saturation is obtained when the windings 71 are carrying predetermined values of both their direct and alternating current components within the desired range of energization of the relay.

Although the invention has been described with reference to certain specific embodiments thereof, numerous modifications thereof are possible. Therefore, the invention is to be restricted only by the appended claims as interpreted in view of the prior art.

We claim as our invention:

1. In an electroresponsive, alternating-current instrument having terminals, a rotor assembly, a stator assembly, means mounting said rotor assembly for movement relative to said stator assembly, damping means associated with said assemblies for retarding movement of said rotor assembly relative to said stator assembly, and means associated with said assemblies for producing, when energized through the terminals from an alternating current source, a plurality of phase-displaced alternating magnetic fluxes acting on said assemblies to produce relative movement therebetween, said alternating magnetic fluxes being effective for producing a force acting between said assemblies which varies in magnitude as a function of the phase displacement between said magnetic fluxes, and a rectifier unit connected for energization from the terminals for producing a direct-current output varying as a function of the input to the unit, said assemblies including means responsive to the direct-current output for changing the phase displacement between said magnetic fluxes.

2. In an electroresponsive, alternating-current instrument, a rotor assembly, a stator assembly, means mounting said rotor assembly for movement relative to said stator assembly, damping means associated with said assemblies for retarding movement of said rotor assembly relative to said stator assembly, means associated with said assemblies for producing, when energized, a plurality of phase-displaced alternating magnetic fluxes acting on said assemblies to produce relative movement therebetween, said alternating magnetic fluxes being effective for producing a force acting between said assemblies which varies in magnitude as a function of the phase displacement between said magnetic fluxes, one of said assemblies providing a magnetic path for one of said magnetic fluxes which is saturable independently of the path for the other of said magnetic fluxes, and direct-current means responsive to the energization producing the alternating magnetic fluxes for controlling the saturation of the saturable magnetic path within the range of operation of said instrument to change the phase displacement between said magnetic fluxes.

3. In an electroresponsive, alternating-current instrument, a rotor assembly, a stator assembly, means mounting said rotor assembly for movement relative to said stator assembly, damping means associated with said assemblies for retarding movement of said rotor assembly relative to said stator assembly, and means associated with said assemblies for producing, when energized, a plurality of phase-displaced alternating magnetic fluxes acting on said assemblies to produce relative movement therebetween, said alternating magnetic fluxes being effective for producing a force acting between said assemblies which varies in magnitude as a function of the phase displace-

ment between said magnetic fluxes, and lagging means associated with the path of at least one of said magnetic fluxes and adjustable for controlling the phase displacement between said magnetic fluxes, said lagging means comprising a direct-current rectifier connected for energization in accordance with a predetermined variable alternating quantity, and means responsive to the direct-current output of the rectifier for varying the adjustment of said lagging means to vary the phase displacement between said magnetic fluxes.

4. In an electroresponsive, alternating-current instrument, a rotor assembly, a stator assembly, means mounting said rotor assembly for movement relative to said stator assembly, damping means associated with said assemblies for retarding movement of said rotor assembly relative to said stator assembly, and means associated with said assemblies for producing, when energized, a plurality of phase-displaced alternating magnetic fluxes acting on said assemblies to produce relative movement therebetween, said alternating magnetic fluxes being effective for producing a force acting between said assemblies which varies in magnitude as a function of the phase displacement between said magnetic fluxes, lagging means associated with the path of at least one of said magnetic fluxes for controlling the phase displacement therebetween, said lagging means including an impedance having a magnetic core for controlling the magnitude of lagging by the lagging means, and direct-current means responsive to a predetermined variable quantity for saturating said magnetic core to vary the phase displacement between said magnetic fluxes.

5. In an induction instrument responsive to an alternating electrical quantity, a magnetic structure having a plurality of pole pieces defining an air gap, an electro-conductive armature, means mounting said armature for rotation in said air gap, circuit means effective when energized in accordance with a predetermined alternating quantity for producing a plurality of phase-displaced alternating magnetic fluxes in said pole pieces and air gap, said magnetic fluxes acting on said armature to urge said armature in a predetermined direction relative to said magnetic structure, said circuit means having impedance values selected to provide a phase displacement between the magnetic fluxes for low values of energization of the instrument having a value differing from the value giving optimum torque urging the armature in said direction, damping means associated with said armature for retarding movement thereof, and means responsive to an increase in the energization producing one of said magnetic fluxes for varying the impedance values and thereby varying the phase displacement of said magnetic fluxes to increase the torque applied to said armature by said magnetic fluxes.

6. In an electroresponsive induction instrument, an electroconductive armature, actuating means including first winding means effective, when energized, for producing a first alternating magnetic flux acting on said armature, and second winding means effective, when energized, for producing a second alternating magnetic flux acting on said armature, said magnetic fluxes cooperating to develop a force acting on said armature which is a function of the phase displacement between said magnetic fluxes, means mounting said armature for movement relative to said actuating means, damping means for retarding movement

of said armature relative to said actuating means, and magnetic means associated with said actuating means for establishing low reluctance paths for magnetic flux produced as a result of energization of said winding means, the phase displacement of the magnetic fluxes being dependent on the relative magnetic permeabilities of the low reluctance paths, said magnetic means including a portion associated with one of said magnetic fluxes, said portion being saturable within the range of operation of said instrument in advance of saturation of the portion of the magnetic means associated with the other of the magnetic fluxes for varying the phase relationship between said magnetic fluxes to increase the force acting on said armature.

7. In an electroresponsive induction relay, an electroconductive armature, bearing means supporting said armature for rotation, and actuating means including a saturable magnetic structure responsive to a variable quantity for applying to said armature a pair of alternating magnetic fluxes which are space and phase displaced to develop a torque between said armature and said actuating means which is dependent on the magnitude of said magnetic fluxes and the phase displacement therebetween, said actuating means including the saturable magnetic structure being proportioned to provide magnetic fluxes having a phase displacement below the value producing optimum torque for a predetermined range of operation of the relay, said saturable magnetic structure operating as a lagging control means for one of the magnetic fluxes energized in accordance with one of said magnetic fluxes, said magnetic structure being proportioned to saturate when said one magnetic flux exceeds a predetermined value to vary the phase displacement between said magnetic fluxes towards a value giving optimum torque.

8. In an electroresponsive inverse-time, induction relay, a magnetic structure having an air gap, said magnetic structure including first and second pole means having pole faces adjacent said air gap, first winding means associated with said first pole means, said winding means being effective when energized by alternating current for directing a first magnetic flux through said air gap, second winding means associated with said second pole means, said second winding means being effective when energized by alternating current for directing a second magnetic flux through said air gap, an electroconductive armature, means mounting said electroconductive armature for rotation in said air gap, damping means associated with said armature, said magnetic fluxes being physically spaced to produce a torque acting on said armature which is dependent on the magnitudes of the magnetic fluxes and on the phase displacement thereof, said magnetic structure and the winding means having impedances selected to provide magnetic fluxes having a phase displacement which is other than the value producing optimum torque when one of said alternating currents is below a predetermined value, and means responsive to said one alternating current when it exceeds its said predetermined value for adjusting said phase displacement towards the value producing optimum torque.

9. In an electroresponsive inverse-time, induction relay, a magnetic structure having an air gap, said magnetic structure including first and second pole means having pole faces adjacent said air gap, first winding means associated with said first pole means, said winding means being

effective when energized by alternating current for directing a first magnetic flux through said air gap, second winding means associated with said second pole means, said second winding means being effective when energized by alternating current for directing a second magnetic flux through said air gap, and electroconductive armature, means mounting said electroconductive armature for rotation in said air gap, damping means associated with said armature, said magnetic fluxes being physically spaced to produce a torque acting on said armature which is dependent on the magnitudes of the magnetic fluxes and on the phase displacement thereof, said magnetic structure and the winding means having impedances selected to provide magnetic fluxes having a phase displacement dependent on the relative permeabilities of the associated portions of said magnetic structure which is other than the value producing optimum torque when one of said alternating currents is below a predetermined value, the portion of said magnetic structure associated with the leading one of said magnetic fluxes being designed to saturate in advance of saturation of the portion of the magnetic structure associated with the remaining one of said magnetic fluxes when said magnetic flux increases within the range of operation of the relay above a predetermined value to increase the phase displacement of said magnetic fluxes towards the value producing optimum torque.

10. In an electroresponsive inverse-time, induction relay, a magnetic structure having an air gap, said magnetic structure including first and second pole means having pole faces adjacent said air gap, first winding means associated with said first pole means, said winding means being effective when energized by alternating current for directing a first magnetic flux through said air gap, second winding means associated with said second pole means, said second winding means being effective when energized by alternating current for directing a second magnetic flux through said air gap, an electroconductive armature, means mounting said electroconductive armature for rotation in said air gap, damping means associated with said armature, said magnetic fluxes being physically spaced to produce a torque acting on said armature which is dependent on the magnitudes of the magnetic fluxes and on the phase displacement thereof, said magnetic structure and the winding means having impedances selected to provide magnetic fluxes having a phase displacement which is other than the value producing optimum torque when one of said alternating currents is below a predetermined value, and means responsive to said one alternating current when it exceeds its said predetermined value for adjusting said phase displacement towards the value producing optimum torque, said last-named means comprising a lagging coil associated with one of said magnetic fluxes, and means responsive to said one alternating current for varying the impedance of said lagging coil to increase the phase displacement between said magnetic fluxes towards the value producing optimum torque when said one alternating current is above a predetermined value.

11. In an electroresponsive inverse-time, induction relay, a magnetic structure having an air gap, said magnetic structure including first and second pole means having pole faces adjacent said air gap, first winding means associated with said first pole means, said winding means being effective when energized by alternating current for

directing a first magnetic flux through said air gap, second winding means associated with said second pole means, said second winding means being effective when energized by alternating current for directing a second magnetic flux through said air gap, an electroconductive armature, means mounting said electroconductive armature for rotation in said air gap, damping means associated with said armature, said magnetic fluxes being physically spaced to produce a torque acting on said armature which is dependent on the magnitudes of the magnetic fluxes and on the phase displacement thereof, said magnetic structure and the winding means having impedances selected to provide magnetic fluxes having a phase displacement which is other than the value producing optimum torque when one of said alternating currents is below a predetermined value, and means responsive to said one alternating current when it exceeds its said predetermined value for adjusting said phase displacement towards the value producing optimum torque, said last-named means comprising a lagging coil associated with one of said magnetic fluxes, an inductor, means connecting said inductor with said lagging coil in a series circuit, said inductor having a saturable magnetic core, and means responsive to increase of said one alternating current above a predetermined value for saturating said magnetic core to decrease the impedance of said series circuit.

12. In an electroresponsive induction instrument a stator assembly, an electroconductive armature, means mounting said armature for ro-

5 tation relative to said stator assembly, alternating current responsive means for actuating said armature including a plurality of windings on said stator effective when energized in series from a source of alternating current for supplying magnetic flux to said armature, and means for damping rotation of said armature, said damping means comprising a pair of half-wave rectifiers connected in series opposition, and means connecting a separate portion of said windings across each of said rectifiers.
